UNITED STATES PATENT OFFICE.

CLARENCE A. SHALER, OF WAUPUN, WISCONSIN.

VULCANIZING APPARATUS.

1,312,364.

Specification of Letters Patent. Patented Aug. 5, 1919.

Application filed December 15, 1915. Serial No. 66,886.

To all whom it may concern:

Be it known that I, CLARENCE A. SHALER, a citizen of the United States, residing at Waupun, county of Fond du Lac, and State 5 of Wisconsin, have invented new and useful Improvements in Vulcanizing Apparatus, of which the following is a specification.

My invention relates to improvements in vulcanizing apparatus.

10 The object of my invention is to provide a simple, compact and inexpensive form of vulcanizer of that type in which the heater is inclosed and the articles to be vulcanized are fully protected from direct contact with 15 the flame and gases of combustion. Also to provide a vulcanizer of the described class in which a measured charge of combustible may be inserted in the form of a cartridge and in which combustion will be so regulated 20 that the heat of the vulcanizing surface will be gradually raised to the desired temperature and maintained at a vulcanizing temperature for a sufficient period to effect a thorough vulcanization without further attention on the part of the user, the 25 heat being then reduced by reason of the exhaustion of the fuel supply.

In the drawings—

30 Figure 1 is an elevation of my improved vulcanizer with a portion of the casing broken away in vertical section to disclose the fuel containing cartridge and the heat conducting and combustion regulating baffle walls.

35 Fig. 2 is a vertical sectional view of the same, drawn to a plane on line $x-x$ of Fig. 1, with the clamping lever illustrated in full.

Fig. 3 is a transverse sectional view drawn on line $y-y$ of Fig. 1.

40 Like parts are identified by the same reference characters throughout the several views.

The casing 1, of a generally rectangular form, has one side wall provided with a flat 45 vulcanizing surface 2. The opposing side wall is provided with a concave vulcanizing surface 3, this surface being adapted to fit the outer surface of a tire casing when inflated. The lower end of the casing is provided with foot pieces 4 and 5, and the upper end is provided with a forked projection 6. A clamping lever 7 is pivoted at 8 to the foot piece 5, and the upper end of this lever is apertured to receive a clamping bolt 10, 55 said bolt being adapted to be received be-

tween the arms of the fork 6 with the head 11 of the bolt engaging said arms. A thumb nut 12 is threaded upon the bolt and adapted to bear upon the upper end of the clamping lever 7. A plate 15 is swiveled to the central portion of the lever 7 by means of a headed pin or bolt 16. The outer surface of the plate 15 is provided with a rounded boss 17 through which the swiveled bolt passes, whereby said plate is free to oscillate in all 60 directions in rocker bearing contact with the lever 7. The inner surface of the plate is recessed to receive a pad 18, which conforms substantially in contour to the contour of the vulcanizing surface 2. This pad is 65 adapted to be clamped against the vulcanizing surface 2, or against an article engaged between it and said vulcanizing surface by means of the lever 7, bolt 10 and thumb nut 12. When it is desired to release the article 70 thus clamped against the vulcanizing surface, the thumb nut 12 is loosened sufficiently to allow the bolt 10 to swing upwardly from between the forked arms of the projection 6, whereupon the lever 7 may be swung outwardly to any desired distance. The aperture in the lever through which the bolt 10 passes, is elongated vertically to facilitate 75 the manipulation of the bolt 10 into and out of the position between the forked arms in 80 which the bolt is illustrated in Fig. 2.

The plate 15 is also provided with projecting ears 20 and 21 respectively, these ears being connected with the edge margins of the plate. These ears are apertures or 90 forked to receive bolts 23 connected with a chain 24 adapted to pass around the inflated tire casing and the rim of a wheel, whereby the vulcanizer may be clamped in position with its concave face bearing upon the casing by means of thumb nuts 25.

The walls provided with the vulcanizing faces are interiorly connected with each other by suitably apertured partitions 27 and 28. These partitions not only serve as 100 baffles to distribute the flame and products of combustion within the casing, but also transmit heat to the vulcanizing surfaces, the baffles being integrally connected with the casing walls directly opposite the vulcanizing surfaces. The baffle walls are also suitably spaced so that the heat delivered 105 to the vulcanizing surfaces by conduction will be properly distributed. Apertures 29 in these baffle walls are of such size as to 110

5 permit delivery of the smoke and gases of combustion to one or more outlets 30 at the upper end of the casing and also to regulate or control the combustion, since the baffle plates or partitions will serve as non-adjustable dampers.

A cylindrical cartridge is adapted to be inserted into the casing through an aperture 36 formed in one edge wall of the casing. 10 This cartridge is provided with a handle 37 composed of non-heat conducting material. The body of the cartridge comprises a perforate cylinder 35 filled with non-combustible absorbent material 38. This material 15 preferably comprises a body of asbestos wicking, which, when the cartridge is inserted in a quantity of liquid fuel, will absorb a sufficient quantity of fuel to maintain combustion for a definite interval under 20 the conditions existing within the casing. It will be observed that the casing is provided with a draft aperture 40 underneath the cartridge and with additional draft apertures 41 in the edge margins above the cartridge. The cartridge is also loosely fitted to the aperture 36 so that a small quantity of air is permitted to enter through this aperture.

In operation, the vulcanizer being 30 clamped upon the article to be repaired, the cartridge is removed from the vulcanizer casing and immersed in liquid fuel, the filling 38 becoming immediately saturated therewith. The cartridge is then re-inserted 35 in the casing through the aperture 36 to the position in which it is illustrated in Fig. 1. The combustible may then be readily ignited by holding a lighted match underneath the aperture 40. The liquid 40 will burn slowly for a short period during which the temperature of the casing will be gradually raised until the heat of the cartridge becomes sufficient to vaporize the liquid contained therein. In the meantime, 45 a draft will be created within the casing and currents of air will enter the casing rapidly through the aperture 41, so that the vaporized combustible will be supplied with sufficient oxygen to maintain sufficiently perfect combustion within the casing and to 50 confine the flame to the interior of the casing instead of having the gases partially oxidized above the casing with a resulting exposed flame.

55 The size of the cartridge will of course depend upon the character or density of the liquid fuel employed. The cartridge will be of such size as to maintain combustion for the desired period, the fuel becoming exhausted 60 when the heat has been maintained long enough to effect a proper vulcanization. It will of course be understood that the device is intended for repairing cuts and punctures in vehicle tires and tire casings, and 65 that the vulcanizing operations herein re-

ferred to are such operations as are performed for repair purposes.

I claim—

1. A vulcanizer including a heater casing having one side face adapted to receive the 70 article to be vulcanized, in combination with a clamping member adapted to engage and hold the article against said face, an operating lever pivoted to the lower end of the casing, and loosely connected intermediate 75 of its ends with said clamping member, a clamping bolt adjustably secured to the upper end of the lever and adapted to removably engage with the upper end of the casing, and means for maintaining combustion 80 for a limited period in the lower portion of the casing.

2. A vulcanizer including a heater casing having one side face adapted to receive the 85 article to be vulcanized, in combination with a clamping member adapted to engage and hold the article against said face, an operating lever pivoted to the lower end of the casing, and loosely connected intermediate 90 of its ends with said clamping member, a clamping bolt adjustably secured to the upper end of the lever and adapted to removably engage with the upper end of the casing, said upper end of the casing having a forked projection adapted to loosely 95 receive the bolt between the arms thereof, and means for maintaining combustion for a limited period in the lower portion of the casing.

3. A vulcanizer, including the combination of a casing having a flat side wall, and another side wall having a vertically extending concave channel, a lever pivotally connected with the lower end of the casing and extending vertically along the flat 100 side wall, a clamping plate loosely connected with the lever and adapted to engage a rubber tube between it and said flat side wall, adjustable clamping connections between the lever and the casing, and means 105 for maintaining combustion for limited periods in the lower end of said casing.

4. A vulcanizer, including the combination of a casing having a flat side wall, and another side wall having a vertically extending concave channel, a lever pivotally connected with the lower end of the casing and extending vertically along the flat side wall, a clamping plate loosely connected with the lever and adapted to engage a rubber tube 110 between it and said flat side wall, adjustable clamping connections between the lever and the casing, and means for maintaining combustion for limited periods in the lower end of said casing, said casing being vented in 115 its upper portions and having heat conveying baffles connecting said side walls and adapted to conduct heat of combustion to the respective vulcanizing faces.

5. A vulcanizer, comprising the combina- 130

- tion of a chamber fuel containing casing, a cartridge provided with absorbent material, and adapted to be received in one end of the casing, supporting brackets adapted to support the casing in an upright position, with the cartridge at the lower end, a clamping lever pivoted to one of the brackets, and having a clamping bolt at its other end, a slotted member connected with the casing at its upper end, adapted to receive the headed end of the clamping bolt, and a clamping plate having swivel connection with an intermediate portion of the lever.
6. In a vulcanizer, including a casing having a vulcanizing side face, draft apertures in its bottom portion and vent apertures in its top portion, in combination with a removable charging cartridge filled with absorbent non-combustible material and provided with perforate walls, and means for supporting the cartridge within the casing and in the vicinity of said draft apertures, together with a vertically disposed clamping lever pivotally connected with the casing at one end, and adapted for adjustable connection therewith at the other end and a clamping plate in rocker bearing connection with the lever; said plate being adapted to engage articles to be vulcanized between it and said vulcanizing face.
7. In testimony whereof I affix my signature in the presence of two witnesses.
